US0D1104257S

(12) **United States Design Patent** (10) **Patent No.:** **US D1,104,257 S**
(45) **Date of Patent:** **** Dec. 2, 2025**

(54) **BUBBLE TRAP**

(71) Applicant: **Life Technologies Corporation**,
Carlsbad, CA (US)

(72) Inventors: **Scott T. Hanks**, Smithfield, UT (US);
Steven R. Kjar, Logan, UT (US)

(73) Assignee: **Life Technologies Corporation**,
Carlsbad, CA (US)

(**) Term: **15 Years**

(21) Appl. No.: **29/853,639**

(22) Filed: **Sep. 16, 2022**

(51) **LOC (15) Cl. 24-04**

(52) **U.S. Cl.**

USPC **D24/121**

(58) **Field of Classification Search**

USPC D24/110.6, 111, 115, 117, 121, 127, 109,
D24/197

CPC B01L 5/02; B01L 5/04; B01L 3/12

(57) **CLAIM**

The ornamental design for a bubble trap as shown and described.

DESCRIPTION

FIG. 1 is a top perspective view of a bubble trap wherein the ovoid body is translucent;

FIG. 2 is a bottom left perspective view thereof;

FIG. 3 is a bottom right perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right side elevational view thereof; and,

FIG. 9 is a left side elevational view thereof.

The broken lines showing features of the design are for the purpose of illustration only and form no part of the claimed design.

1 Claim, 9 Drawing Sheets
